UNITED STATES PATENT OFFICE.

WILLIAM Q. TOLMAN, OF NEW BEDFORD, MASSACHUSETTS, ASSIGNOR TO
THE PAIRPOINT MANUFACTURING COMPANY, OF SAME PLACE.

DESIGN FOR A BOX.

SPECIFICATION forming part of Design No. 24,032, dated February 12, 1895.

Application filed January 16, 1894. Serial No. 497,109. Term of patent 7 years.

To all whom it may concern:

Be it known that I, WILLIAM Q. TOLMAN, of New Bedford, in the county of Bristol and State of Massachusetts, have invented and produced a new, useful, and original Configuration of a Box, of which the following is a specification, reference being had to the accompanying drawings, in which—

Figure 1 is a plan of a box containing my design, a part being broken away for greater clearness. Fig. 2 is a central sectional view of said box.

The leading feature of my design is a hat-shaped box having a bottom which slopes upwardly from the bottom of the box and which

is extended into a flat surface at the upper edge of the box, at one side thereof.

In the drawings, A is the box composed of the side piece a and bottom a' which is surrounded by a flange a^2 . Bottom a' slants upwardly toward the rim of the box, but, at a^3 , is bent and extended straight out to the box rim.

What I claim is—

The design for a box herein shown and described.

WILLIAM Q. TOLMAN.
